LINE CASTING MACHINE

Samuel E. Sperry, Hollis, N. Y., assignor to Intertype Corporation, Brooklyn, N. Y., a corporation of New York

Application July 20, 1932, Serial No. 623,630,
and in Germany August 23, 1931

9 Claims. (Cl. 199—51)

The present invention relates to improvements in line casting machines and more especially to those of the general class shown and described in U. S. Letters Patent No. 436,532, granted September 16, 1890, wherein a line of assembled character bearing matrices, usually containing expandable spacebands, is received and lowered by a so-called first elevator to a position in front of a mold and the mold is then brought forward into cooperation with the matrix line, the line is justified by expanding the spacebands therein, after which molten metal is injected into the mold to cast a type bar or slug against the character bearing face of the matrix line, following which the mold recedes from the matrix line, breaking away the character bearing edge of the slug cast therein from the matrices and allowing the elevator to remove the matrix line for distribution of the matrices therefrom, and the invention relates more particularly to machines of this class as now generally constructed to use matrices provided with type forming characters at upper and lower levels thereon and embodying means for stopping the descent of the elevator at either a lower or an upper alignment position to bring the upper or lower matrix characters to the casting level relatively to the mold.

In the operation of machines of this class as heretofore constructed, in casting from the matrix line while the latter is positioned at the upper casting level, the elevator supporting the matrix line usually sags or drops slightly when the mold breaks away from the matrix line, and this has caused damage to and mutilation of the type characters cast on the type bar or slug, and one of the objects of the present invention is to provide relatively simple and effective means for supporting the elevator and the matrix line therein at such time to prevent such sagging or dropping thereof and thereby avoid such damage or mutilation of the type characters, such supporting means for the elevator being preferably controlled or operative by elements already present in the usual machines of this class.

Also, in the operation of machines of this class as heretofore constructed, the usual or so-called first elevator which presents the matrix line to the mold, either at the usual lower casting level or at an upper casting level, has a tendency to be lifted by the upward force exerted by the justification bar in justifying the matrix line during the usual first justification period, especially when the line contains a relatively large number of expandable spacebands, resulting in

binding of the lower lugs on the matrices against the underside of the usual alining rib or rail on the mold and against the rails in the elevator, in consequence of which proper and complete filling out or justification of the line to full line measure has been interfered with or prevented and the slug cast from such a line has been defective. It is an object of the present invention to provide novel and effective means for preventing the first elevator from being driven upwardly during justification of the line and to thereby overcome the above noted difficulty and objection, such means being capable of control or operation from elements already present on the usual machines of this class.

A further object of the invention is to provide a single means which is operative at the appropriate times in the cycle of operation of the machine to prevent upward or downward movement of the first elevator or member which presents the matrix line to the mold, the same means thereby preventing interference with the proper and complete justification of the line and also preventing sagging or dropping of the elevator when the mold breaks away from the matrix line.

To these and other ends, the invention consists in certain improvements and combinations and arrangements of parts all as will be hereinafter more fully described, the features of novelty being pointed out particularly in the claims at the end of the specification.

In the accompanying drawing:

Fig. 1 is an end elevation of a portion of a line casting machine embodying the present invention;

Fig. 2 is a vertical section, on an enlarged scale, taken through the upper portion of the first elevator and through the mold and cooperative parts of the machine; and

Fig. 3 is a horizontal section, on an enlarged scale, taken on the line 3—3 of Fig. 1.

Similar parts are designated by the same reference characters in the different figures.

The invention is shown in the present instance applied to a line casting machine of the general class hereinbefore referred to, such machine comprising, as usual, a main frame 1 which supports the various operative parts of the machine, the usual so-called first elevator 2 which is guided to reciprocate vertically by the usual bevelled or angular guide faces 2^a, in the usual vise frame 3, the first elevator having a head 4 the jaws 5 of which are provided with rails as usual to receive and support a line of matrices M and ex-

5 pansible spacebands which may consist as usual of a tapered or wedge shaped sleeve member S and a relatively longer tapered wedge member S', the line of matrices and spacebands being 10 previously composed in the assembling mechanism of the machine and transferred in the usual and well known way to the first elevator while the latter is positioned at a suitable receiving level. The first elevator, after receiving the 15 matrix line, is lowered to present such line in front of a mold 6 which is formed as usual with a slot 7 in which the type bar or slug is to be cast, the body of the mold being formed on its face with upper and lower grooves 8 and 9 to 20 form upper and lower rails against which the lower rear lugs or ears on the matrices are adapted to aline, the mold being carried as usual by a mold wheel or disk 10 which is mounted as usual on a slide so that it is movable forwardly 25 and rearwardly to bring it into engagement with the rear face of the matrix line preparatory to a cast and to recede therefrom following the cast, to permit rising of the first elevator and the matrix line, after which the matrices and spacebands composing the line are distributed in the usual well known way.

30 While the mold is in engagement with the matrix line and the slot or cavity 7 therein is alined with the type forming characters in the matrices, and after the matrix line has been justified, molten metal is injected into the mold to cast the type bar or slug, the injection of the molten metal being effected usually from a metal pot 11 the throat 11a of which is provided with 35 a mouthpiece 12 which is adapted to engage and form a metal tight joint with the rear face of the mold, the mouthpiece having orifices as usual through which the molten metal is injected into the mold. The mold wheel carrying the mold 40 may be advanced and retracted by the means usually employed in machines of this class for this purpose, and the metal pot may be advanced to form a lock-up between its mouthpiece and the mold and between the mold and the matrix line 45 and retracted by the means usually employed in machines of this class for this purpose.

50 In line casting machines of this class as now commonly constructed, matrices having type forming characters punched or otherwise formed intaglio at different levels therein are used, and the matrix lines are presented to the mold at different levels according to whether the type bar or slug is to be cast from the lower or upper 55 matrix characters. The first elevator is usually lowered and raised to carry the matrix line there- 60 in to and from a position in front of the mold by a lever 13 which is pivoted to the main frame at 14 and is connected by a longitudinally compressible link 15 at its forward end to the elevator 2, the lever 13 being connected to an arm 16 which carries a roller 17 which rides on the periphery of a cam 18 under the weight of the elevator, this cam being mounted on the usual main cam shaft 19 of the machine which is set 65 into operation at an appropriate time or point in the cycle of operations of the machine, as is well known in the art. The cam 18 has a portion 20 with which the roller 17 cooperates while the elevator 2 is in its lowermost position, a portion 21 with which said roller cooperates while the elevator is lifted slightly from its lowermost position to bring the lugs or ears on the matrices into alinement beneath one of the alining rails on the mold, a recessed portion 22 which the roller 17 enters and allows the lifting force ex-

80 erted on the elevator to be relaxed to relieve the upward pressure of the matrix ears on the alining rail of the mold preparatory to retraction of the latter, and the portions 23 and 24 which co-operate with the roller 17 to successively lift the elevator to its uppermost or matrix line removing position and allow the elevator to descend to its intermediate or matrix line receiving position.

85 The vise frame 3 has the usual vise cap 25 and this vise cap is provided with an alining bar 26 which is slidable horizontally in a groove in the top of the vise cap, and the alining bar is provided with one or more pins 27 which project upwardly from its upper surface, the alining bar being shiftable to bring it or one of the pins thereon into position beneath a banking screw 28 mounted in the head 4 of the elevator, the screw 28 engaging directly on the upper side of the bar 26 when the upper character punchings in the matrices are to be alined with the mold, and the screw 28 engaging on the top of one of the pins 27 to arrest the elevator at a relatively higher alinement level, as when the lower character punchings, or character punchings at a third or auxiliary level, as in three-letter matrices or matrices with very 95 large one-letter display characters are to be alined with the mold.

90 The machine also comprises as usual a so-called first justification lever 29 controlled by the usual justification cam on the main cam shaft of the machine and the usual second justification lever 30, the latter being controlled by the usual second justification or vise closing cam 31 on the main cam shaft, these justification levers being operative to force the usual justification bar 32 upwardly against the depending wedges S' of the spacebands contained in the matrix line in the first elevator and to thereby fill out the matrix line to its full line measure between the jaws of the usual vise and to justify the line preparatory to 105 the casting operation, the lever 30 having a roller 33 thereon which is held by a spring 34 against the cam 31, and the latter having depressions 35 and 36 therein at appropriate points in its periphery so that the roller 33 will enter the 110 depression 35 and allow the lever 30 to rise under the action of the spring 34 during the usual first justification, after which the lever 30 will be forced downwardly by the cam 31 as the roller 33 leaves the depression 35, following which the 115 roller 33 will enter the second depression 36 in the cam 31 and will allow the lever 30 to again rise under the action of the spring 34, this ascent of the lever 30 taking place during the usual sec- 120 on justification.

125 The machine as thus far described operates substantially in the manner described in the application of John W. Bittner, Serial No. 547,994, filed June 30, 1931, which has matured into U. S. Letters Patent No. 1,868,445 granted July 5, 1932. In 130 the normal operation of the usual machine of this class, when casting from matrix lines presented to the mold in the normal or lowermost position, which brings the upper matrix characters into position to be alined with the mold slot, the first 135 elevator 2 moves downwardly under control of the cam 18 until the banking screw 28 rests on the top of the slidale alining bar 26, the portion 20 of the cam 18 then engaging the roller 17. The mold wheel 10 carrying the mold 6 in which the slug is to be cast then advances against the line of matrices in the first elevator, the metal pot advances to bring its mouthpiece 12 against the back of the mold, and the first and second justification levers 29 and 30 rise successively to effect 140 145 150

the usual first and second justifications of the matrix line. In order to permit the lower lugs or ears on the matrices to freely enter the alining grooves in the mold, the machine is so constructed as to allow a slight clearance between the upper edges of the matrix ears and the upper face of the mold alining groove 9 when the first elevator is seated on the alining bar 26. After the matrix ears have fully entered the alining groove, the first elevator rises from the alining bar 26 a distance equal to the clearance provided between the matrix ears and the mold alining groove, as described above, in order to press the lower lugs or ears on the matrices firmly upwardly against the upper face of the mold alining groove in order to insure perfect alinement of the matrices, and this slight rise of the elevator to aline the matrices against the mold is effected by the continued rotation of the cam 18 in the direction indicated by the arrow in Fig. 1, which brings the slightly raised portion 21 of the cam into engagement with the roller 17, the movement thus imparted to the roller 17 by the raised portion 21 on the cam being transmitted to the first elevator 2 through the arm 16 and lever 13 and through the yielding or compressible link 15 which connects the lever 13 to the first elevator.

Immediately after the slug is cast in the mold, the cam 18 will have reached a position where the roller 17 is in contact therewith at the recessed portion 22, and the gradual recession or dropping away of this portion of the cam, which is followed by the roller 17, causes the upward drive or lifting force exerted on the elevator to become relaxed, in consequence of which the upper edges of the matrix ears move slightly downwardly or away from the upper face of the lower mold alining groove during the breaking away of the slug or retraction of the mold from the matrix line, so that the matrix ears will not be caused to drag against the upper wall of the mold groove during disengagement therefrom and thereby cause objectionable wear on the parts, although the yielding link 15 will be sufficiently compressed during casting from lines positioned at the normal or lower alinement level to support the weight of the elevator and thus prevent undue dropping or sagging of the matrix line relatively to the mold.

In casting slugs from matrix lines while the latter are in an upper or high alinement position, as when the lower matrix characters are alined with the mold slot, the actions are generally the same as just described except that the first elevator is stopped in its descent by a high alinement pin 27 on the alining bar 26 and the elevator is lifted from this pin to aline the matrix ears against the mold preceding the cast. This higher position occupied by the first elevator, however, causes the roller 17 to leave contact with the cam 18 when the recessed or receding portion 22 of the cam comes opposite to the roller, because the first elevator is arrested in its descent by the high alinement pin 27, and the roller 17, lever 13 and link 15 are then unable to support the first elevator in such high alinement position. Consequently, when the mold retracts or breaks away from the matrix line following the cast at the upper alinement position of the first elevator, the latter has heretofore been permitted to drop onto the high alinement pin, and the weight of the first elevator which was brought to bear on the type character face of the slug and which still projected into the character punchings of the matrices, which latter are held immovably in the

jaws of the first elevator, has subjected the type character face to a shearing action which, due to the softness of the type metal comprising the slug, damaged or mutilated the type characters, the compression of the yielding link 15 being insufficient to avoid dropping of the first elevator when the slug or mold breaks away, owing to the higher position then occupied by the first elevator.

The present invention provides novel means for sustaining the weight of the first elevator, during casting from the matrix line while in the high alinement position, when the roller 17 is opposite the portion 22 of the cam 18 and hence the elevator is unsupported by such cam against dropping during the break-away of the mold or withdrawal of the characters on the slug from the character punchings in the matrices from which the slug was cast, thereby avoiding damage or mutilation of the cast type characters, especially those having descending stems, through the shearing action described above.

According to the present invention, such auxiliary supporting means for the first elevator comprises a friction shoe or clamping device to engage the first elevator to prevent undue dropping of the latter during break-away of the mold from the matrix line while casting therefrom when the line is in high alinement position at which time the roller 17 is out of contact with the cam 18. According to the particular embodiment of the invention shown, a lever 37 is pivotally mounted on the rigid vise frame 3 by means of a shoulder screw 38, this lever being provided near its pivoted end with a boss 39 in which is threaded an adjustable screw 40 provided with a lock nut 41. The inner end of the screw 40 is provided with a ball point which has a universal bearing in a steel or other suitable friction shoe 42, the latter having a face which bears frictionally on the adjacent bevelled or angular edge 2^a of the vertically movable first elevator. The opposite or rear end of the lever 37 carries a plunger 43 having a spherical or rounded head 44 thereon and a spring 45 interposed between the lever 37 and the plunger 43 acts to yieldingly press the head 44 toward one arm of the usual fork 30^a on the forward end of the justification lever 30, the upper edge of this arm of the fork being preferably bevelled as at 30^b to facilitate engagement of the head 44 therewith. A pin 46 is provided on the vise frame to serve as a stop to limit the swing of the lever 37 in one direction and thereby insure positioning of the head 44 above the bevelled portion 30^b so that it will be engaged thereby when the justification lever 30 rises.

In operation, the justification lever 30, under control of its usual cam 31 and spring 24, has its roller 33 in contact with said cam near the end of the depression 36 therein as shown in Fig. 1 at the time break-away of the mold from the matrix line takes place, and the lever 37 provided by the present invention is located at such a height and position as to be actuated by the justification lever 30 the movement of which occurs at the proper time in the machine cycle and may be conveniently used to operate the lever 37. The justification lever 30, on its upward movement under the action of its spring 34 and as permitted by the depression 36 in the cam 31, brings the bevelled portion 30^b of its fork 30^a upwardly into engagement with the ball head 44 carried by the lever 37, thereby turning the latter about its pivot screw 38 in a direction to

- cause the screw 40 to force the friction shoe 42 yieldingly against the bevelled or angular guiding face 2^a on the first elevator just prior to the break-away of the mold from the matrix line.
- 5 The first elevator is thereby sustained in raised position above its high alinement stop pin 27 a few thousandths of an inch as represented by the small space between this pin and the screw 28 in the head of the first elevator as shown in Fig. 2, and the first elevator will be thus held in such raised position until the lever 30 moves downwardly out of engagement with the spring pressed plunger 43, which will take place when the cam 31 rotates sufficiently to bring the roller 33 to the highest part of the cam. Engagement of the lever 30 with the spring plunger 43 will, however, be of sufficient duration to permit full break-away of the mold from the matrix line and thus prevent any damage to the letters or character-bearing edge on the slug.
- 10 While the friction shoe or clamping device just described is operative to prevent undue sag of the first elevator from its lifted matrix alining position, that is, it will support or hold the first elevator substantially in such lifted position during the mold break-away when the lifting force exerted on the first elevator is relaxed, such device does allow a slight drop or sag of the first elevator to release the pressure of the lower lugs of the matrices against the alining rail on the mold as the break-away of the mold takes place. When casting in either the lower or upper position, the friction shoe 42 will have been pressed against the first elevator to hold it at about the same instant that the approach end of the depression 22 in the cam 18 comes opposite to the roller 17, and the relaxation of the spring link 15 having taken place, the first elevator is left supported only by the friction shoe, 25 in either casting position, without any upward driving force acting on the elevator. With only the friction shoe supporting the elevator, there is a natural yield and take up of slack or play in the friction shoe carrying members and in the joints thereof such as the joint between the friction shoe 42 and the screw 40 and between the lever 37 and its pivot screw 38, due to the tolerance of fits between these parts of the friction shoe supports, under the weight of the elevator, 30 to avoid any objectionable rubbing of the lugs of the matrices on the alining rail of the mold at the mold break-away period, there being no upward pressure exerted on the elevator at such time by the spring link 15, either while casting at the lower or the upper position, relaxation of the upward drive of the spring link 15 at the mold break-away period taking place, while casting at the lower position, when the depression 22 comes opposite to the roller 17, and, while casting 35 at the upper position, by the disengagement of the roller 17 from the cam 18 when the depression 22 therein comes opposite to said roller.
- The friction or clamping shoe 42 and its actuating lever 37, according to the present invention, also serve, at another point in the cycle of operation of the machine, to retain the first elevator from being forcibly driven upwardly.
- 40 It is well understood by those familiar with machines of this class that, when the usual spaceband justification bar 32 moves upwardly under the influence of the first justification lever 29 (Fig. 3), the spacebands are intended to expand and spread the matrices in the line tightly between the vise jaws, during which time the line 45 is presented face-wise against the mold. It has

been found that certain difficulties arise in justifying lines containing a relatively large number of spacebands. As soon as the justification bar 32 strikes and slightly moves the spaceband wedges S' upwardly, the friction on the one hand between these wedges and their cooperating sleeve members S, when a large number of spacebands are present in the line, added to the resistance on the other hand offered by the matrices against movement longitudinally on the rails in the first elevator jaws 5, is so great as to quickly bring about a tightening or binding effect between the matrices and spacebands. The result is that instead of the spaceband wedges S' being driven upwardly sufficiently to completely spread or justify the line, the upward pressure exerted by the justification bar 32 on the wedges produces a lifting action on the first elevator 2, the lower front lugs m of the matrices being firmly engaged against the under side of the front elevator jaw 5 as shown in Fig. 2, and thereby acting to transmit such lifting action directly to the elevator. Since the lower rear lugs m' of the matrices are also raised, due to this lifting action, these lugs become tightly pressed against the under side of the upper wall of the matrix alining groove in the mold, with the result that further resistance is offered thereby against spreading or justifying of the matrix line tightly between the vise jaws as required. Such a condition results in the formation of hair lines on the slug or improper spacing of the line and the formation of indentations at the ends thereof, which are objectionable.

According to the present invention, the friction or clamping shoe 42 is employed to overcome the above difficulties. As shown in Fig. 1, the cam 31 which controls the second justification lever 30 has a depression 35 in its periphery so that when this portion of the cam is opposite to the roller 33 on the lever 30, the latter is caused to swing upwardly under the influence of the spring 34. This upward swing of the lever 30 takes place in the usual cycle of operations of machines of this class during the first justification period 120 and is usually utilized to give certain desired movement to the left hand vise jaw, as is understood by those skilled in the art and is explained, for example, in U. S. Letters Patent No. 924,243, granted June 8, 1909, such upward swing of the 125 second justification lever 30 occurring at the same time the first justification lever 29 is caused to swing upwardly to actuate the justification bar 32 as described above.

The friction or clamping shoe 42 will therefore 130 be actuated by the rise of the lever 30 due to the entry of its roller 33 in the depression 35 in the cam 31 during the first justification period, to firmly clamp and hold the first elevator 2 against the objectionable upward movement hereinbefore 135 referred to, so that the entire pressure exerted by the justification bar 32 will be applied to effectively drive the spaceband wedges upwardly to effect justification, and counteracting resistance to justification of the line will be minimized, 140 the matrices being left free to expand longitudinally in the elevator jaws.

From the foregoing it will be seen that whenever the lever 30 is caused to rise, it will operate the clamping or friction shoe so that the latter 145 will hold the first elevator against undesirable movement, either upwardly or downwardly, such holding of the first elevator occurring during the first justification period and during the break-away of the mold from the matrix line, the clamp-

ing or friction shoe during the rest of the cycle of operation of the machine being relieved of pressure or inactive so that it will not interfere with the required ascending and descending motions

5 of the first elevator. Obviously, the clamping or friction shoe may be utilized either to prevent the first elevator from being forced upwardly during the first justification period or from dropping during the break-away of the 10 mold from the matrix line, but it is preferably employed for both of these purposes, as has been hereinbefore described.

I claim as my invention:

1. In a line casting machine comprising a slug 15 casting mold, a vertically movable member for presenting a line of matrices thereto, means for advancing the mold toward the matrix line to form a lock-up therewith and for retracting the mold after a cast has been made, and means for exerting a lifting force on said member to align the 20 matrices against the mold and for relaxing such lifting force prior to retraction of the mold, means to frictionally engage said member and hold it substantially in its lifted matrix alining position during retraction of the mold.

2. In a line casting machine comprising a slug 25 casting mold, a vertically movable member for presenting a line of matrices thereto, means for advancing the mold toward the matrix line to form a lock-up therewith and for retracting the mold after a cast has been made, means for exerting a lifting force on said member to align the 30 matrices against the mold and for relaxing such lifting force prior to retraction of the mold, and means for justifying a matrix line in said member, means controlled by said justifying 35 means and operative to hold said member against movement either upwardly or downwardly from its lifted matrix line position.

3. In a line casting machine comprising a slug 40 casting mold, an elevator for presenting a line of matrices thereto, means for advancing the mold toward the matrix line to form a lock-up therewith and for retracting the mold after a cast has been made, means for exerting a lifting force on 45 the elevator to align the matrices against the mold and for relaxing such lifting force prior to retraction of the mold, and means for justifying a matrix line in the elevator, a friction member to engage the elevator, and means controlled by 50 said justifying means for operating said friction member to support the elevator substantially in its lifted matrix alining position during retraction of the mold.

4. In a line casting machine comprising an 55 elevator for presenting a line of matrices to a slug casting mold, and means for forcing spacebands in the line upwardly to justify the line, means arranged to frictionally engage the elevator and operative during justification of the line to prevent upward movement of the elevator.

5. In a line casting machine comprising an

elevator for presenting a line of matrices to a slug casting mold, and means for forcing spacebands in the line upwardly to justify the line, means arranged to frictionally engage the elevator and operative by the justifying means during 80 justification of the line thereby to prevent upward movement of the elevator.

6. In a line casting machine comprising an elevator for presenting a line of matrices to a slug casting mold, means for lifting the elevator to align the matrices therein against the mold, and means for forcing spacebands in the line in the elevator upwardly to justify the line, means arranged to frictionally clamp the elevator and operative by the justifying means during justification of the line thereby to prevent forcing of the elevator upwardly beyond matrix alining position to which it is lifted by said lifting means, by the force applied to the spacebands in justifying the line.

7. In a line casting machine comprising an elevator for presenting a line of matrices to a slug casting mold, means for exerting a lifting force on the elevator to align the matrices therein against the mold and for subsequently relaxing such lifting force, and means for forcing spacebands in the line upwardly to justify the line in the elevator, means cooperative with the elevator to prevent either downward or upward movement thereof.

8. In a line casting machine comprising an elevator for presenting a line of matrices to a slug casting mold, means for exerting a lifting force on the elevator to align the matrices therein against the mold and for subsequently relaxing such lifting force, and means for forcing spacebands in the line upwardly to justify the line in the elevator, holding means to cooperate with the elevator, and means for operating said holding means to hold the elevator substantially 115 in its lifted matrix alining position after relaxation of the lifting force by said lifting means and to hold the elevator against upward movement during justification of the matrix line.

9. In a line casting machine comprising a slug 120 casting mold, an elevator for presenting a line of matrices to the mold, means for advancing the mold toward the matrix line to form a lock-up therewith and for retracting the mold after a cast has been made, means for exerting a lifting 125 force on the elevator to align the matrices therein against the mold and for relaxing such lifting force prior to retraction of the mold, and means for forcing spacebands in the line upwardly to justify the line, holding means to cooperate with the elevator, and means for operating said holding 130 means to support the elevator substantially in its lifted matrix alining position during retraction of the mold and for preventing forcing of the elevator upwardly during justification of the 135 line.

SAMUEL E. SPERRY.
